UNITED STATES PATENT OFFICE

153,489

DESIGN FOR AN ASH TRAY OR SIMILAR
ARTICLEGarfield L. Beckstrom and Richard S. Krause,
Chicago, Ill., assignors to Autopoint Company,
Chicago, Ill., a corporation of Illinois

Application January 29, 1949, Serial No. 566

Term of patent 14 years

(Cl. D85—2)

To all whom it may concern:

Be it known that we, Garfield L. Beckstrom and Richard S. Krause, citizens of the United States, residing at Chicago, in the county of Cook and State of Illinois, have invented a new, original, and ornamental Design for an Ash Tray or Similar Article, of which the following is a specification, reference being had to the accompanying drawing, forming a part thereof.

In the drawing:

Figure 1 is a top plan view of an ash tray or similar article embodying our design.

Fig. 2 is a front elevational view thereof; and Fig. 3 is an end elevational view thereof.

We claim:

The ornamental design for an ash tray or similar article, substantially as shown.

GARFIELD L. BECKSTROM.
RICHARD S. KRAUSE.
